UNITED STATES PATENT OFFICE.

SAMUEL BURDETT ROBESON AND WALTER THAYRE BOHNE, OF NEW ORLEANS, LOUISIANA.

MACHINE FOR CLEANING WATER-TUBES OF BOILERS.

SPECIFICATION forming part of Letters Patent No. 582,953, dated May 18, 1897.

Application filed June 9, 1896. Serial No. 594,882. (No model.)

To all whom it may concern:

Be it known that we, SAMUEL BURDETT ROBESON and WALTER THAYRE BOHNE, citizens of the United States, residing at New Orleans, in the parish of Orleans and State of Louisiana, have invented certain new and useful Improvements in Machines for Cleaning Water-Tubes of Boilers and other Tubes; and we do declare the following to be a full, clear, and exact description of the invention, such as will enable others skilled in the art to which it appertains to make and use the same.

Our invention relates to improvements in apparatus for cleaning the tubes of steam-boilers and other apparatus or machinery; and it has for one of its objects to provide such an apparatus in which the power for actuating the cleaning device is applied direct thereto.

Another object of the invention is to provide an apparatus for the purpose stated embodying such a construction that it may be readily adjusted and adjustably fixed, so as to permit of the cleaning device entering and being actuated in the several tubes or other apparatus.

Still another object is to provide an apparatus for the purpose stated embodying means whereby the cleaning device may be readily inserted in and withdrawn from the tubes or other apparatus and whereby it may be adjusted and adjustably fixed to clean the tubes in sections throughout the length thereof.

Other objects and advantages of the invention will be fully understood from the following description and claims when taken in conjunction with the accompanying drawings, in which—

Figure 1 is an elevation of the cleaning device of our apparatus with a portion of the rod broken away. Fig. 2 is a vertical sectional view illustrating our improved apparatus and a portion of a steam-boiler with the cleaning device in its operative position in one of the boiler-tubes. Fig. 3 is a detail sectional view illustrating the manner in which the toothed plates or bars of the cleaning device operate to remove the scale from the water-tubes of a boiler or from other tubes. Fig. 4 is an enlarged transverse section taken through one of the water-tubes of a boiler with the clean-

ing device in position therein to illustrate the relative position of the several toothed plates or bars of the cleaning device. Fig. 5 is a front elevation of the apparatus. Fig. 6 55 is an enlarged detail section taken in the plane indicated by the line x x of Fig. 5. Fig. 7 is a similar section taken in the plane indicated by the line w w of Fig. 1. Fig. 8 is a detail section, partly in elevation, showing a modified construction of cleaning device and a coupling for connecting the cleaning device and the threaded rod. Fig. 9 is a section taken in the plane indicated by the line y y of Fig. 8, and Fig. 10 is a detail perspective view of one of the screws or bolts.

Referring by numerals to said drawings, 1 indicates two brackets which constitute the main frame of our improved apparatus and are designed to be fastened upon the front of 70 the boiler or apparatus to be cleaned, one at each side of the series of water-tubes, in a manner presently to be described. These brackets 1 have their rear edges or sides pitched or inclined, as shown, and upon such inclined edges is arranged the vertically-movable open frame 2, which is preferably of a rectangular form and is designed to be adjusted and adjustably fixed on the brackets 75 1 in a manner also hereinafter to be described. 80

3 indicates the piston-cylinder of a steam-engine, which may in general be of the ordinary construction and have the usual appurtenances—viz., a valve-chest 3^a, a valve 3^b, and a rod or other means for transmitting 85 motion to the valve. Said cylinder 3 contains a piston 3^c, and this piston is fixed on a hollow rod 4, which extends through stuffing-boxes 4^a at the ends of the cylinder, and is provided at its opposite ends with screw-tapped apertures 4^b, and is also preferably provided with an arm 4^c, attached to the valve rod or stem, as shown. In this hollow piston-rod 4 is arranged a threaded rod 5, which forms a portion of the rod of the cleaning device of our improved apparatus. This rod 5 is connected at its forward end, preferably in a swiveled manner, to the rear end of the rod 7, which for the sake of strength and durability is preferably formed by a plurality of 95 suitably-connected longitudinal sections or strips, as shown. This latter rod 7 is pref-

erably of an octagonal form in cross-section, as shown, and it carries the serrated or toothed and transversely-curved plates or bars 9, which have for their function to scrape or cut the scale out of the water-tubes, as better shown in Fig. 3 of the drawings. The said plates or bars 9 are preferably toothed in the manner shown, although they may be provided with teeth of other shape, if desired, and they are fixedly connected at their opposite ends to spring or resilient strips 9^a, which are carried laterally and rearwardly from their point of connection to the plates 9, and are in turn connected by bolts 9^b to the rod 7, and are preferably countersunk in said rod, as shown. In virtue of this manner of connecting the scraping-plates 9 with the rod 7 it will be seen that the cleaning device may be readily inserted in a tube, and that when within the tube they will be yieldingly pressed against the inside of the same, so as to cut and scrape the scale from the same when the cleaning device is reciprocated. The yielding connection of the scraping-plate 9 also permits them to give when they encounter anything that would tend to break them, and thus reduces the liability of breakage to a minimum.

The plates 9 may be arranged upon the rod 7 in any suitable manner. We prefer, however, to arrange them in one or more circular series, as shown, and when more than one series is employed we prefer to arrange the plates of one series in alinement with the spaces between the plates of the next series, so as to thoroughly scrape the entire inner surface of a water or other tube. We also prefer to have the resilient or spring strips 9^a decreased in length toward the forward end 40 of the rod 7—that is to say, to have the spring strips of the forward series of plates 9 of a less length than those of the second series, and so on—so as to enable the rear plates to remove the scale left by the preceding ones. 45 The threaded rod 5 of the cleaning device is provided with a longitudinal groove 5^a, which receives a feather or spline 5^b of a hand-wheel 6, through which the rod 5 extends, as shown. This wheel 6 is journaled in an arm 50 6^a, connected to the cylinder 3, and when it is turned in one direction it will be seen that the rod 5, and consequently the cleaning device, is moved forwardly, and when it is turned in the opposite direction the rod 5 and the 55 cleaning device will be moved rearwardly. In this manner it will be seen that the cleaning device may be readily inserted or withdrawn from a water or other tube and also that the cleaning device may be moved into 60 the tubes to a greater or less extent, so as to clear the same of scale throughout their length.

The piston-cylinder 3 is arranged and secured in the vertically-movable frame 2, as better shown in Fig. 2, and it may be moved vertically with said frame 2 and may also be moved horizontally in said frame, so as to

permit of the cleaning device being inserted in the several tubes of a boiler or other apparatus. This latter horizontal movement of the cylinder 3 is preferably effected through the medium of the turn-screw 10, which is journaled in the end bars of the frame 2 and extends through the threaded aperture 11 in the cylinder-casting 3, as shown, so that when turned in one direction it will move the cylinder toward the left and when turned in the opposite direction will move the cylinder toward the right.

The arrangement of the apparatus with respect to the water-tubes of a boiler is shown in Fig. 2, in which the cleaning device is illustrated as inserted in one of the water-tubes. Now it will be seen that when steam is permitted to pass from a source of supply (not illustrated) through the rubber tube 3^c to the valve-chest 3^a the piston 3^c will be reciprocated in its cylinder and the cleaning device will be reciprocated in the water-tube to remove the scale therefrom. It will also be seen that the power is applied direct to the cleaning device and that therefore it will be reciprocated with great force, which will enable it to quickly cut, scrape, or saw the scale from the water-tube. When the forward portion of a tube is cleared of scale, the engine is stopped and the cleaning device is moved farther into the tube, when the engine is again started, and so on until the tube is cleared of scale throughout its length.

When the cleaning of a tube is completed, the cleaning device is withdrawn from said tube by rotating the wheel 6, and the frame 2 is adjusted and adjustably fixed on the brackets 1, and the cylinder 3 is adjusted in the frame 2 until the cleaning device rests in alinement with another tube of the boiler or other apparatus, when the operation before described is repeated.

In order to permit of the brackets 1 being readily connected to the front of a boiler, we provide said brackets with apertured lugs 12. These lugs 12, when the doors of a boiler are removed, are interposed between the apertured hinge-lugs (not illustrated) of the boiler 105 and connected thereto by pintles or bolts. Said brackets may, however, be connected to the front of a boiler or to any other apparatus in any suitable manner.

The end bars 15 of the frame 2 are connected to the horizontal bars 16 thereof by screws, bolts, or other suitable means, and said end bars 15 are also connected with the oblique bars of the brackets 1 by bolts 19, which take through lugs 17 of the bars 15 and through threaded apertures in straps 18, arranged at the inner sides of the oblique bars of the brackets 1, as better shown in Figs. 5 and 6 of the drawings. By tightening the screws 19 the frame 2 may be adjustably fixed at various elevations on the brackets 1, and when said screws are loosened the frame 2 may be raised or lowered to the position desired and may then be again adjustably fixed.

by tightening said screws. The raising and lowering of the frame 2 may be effected with a block and tackle (not illustrated) or by other suitable means.

5 The horizontal adjustment of the piston-cylinder and its appurtenances in the frame 2 may be readily accomplished by rotating the screw 10, the flexible connection 3^f, between said cylinder and the source of steam-supply, 10 serving to permit of such adjustment.

In Figs. 8 and 9 we have shown a desirable construction of cleaning device and a desirable swivel-coupling for connecting the rod 7^e of said cleaning device with the threaded 15 rod 5^e.

The rod 7^e of the cleaning device has an end section 20, provided with peripheral ribs 21, and also provided with a threaded inner end 22 and sections 23 for the connection of 20 the resilient strips 9^a of the scraping-plates 9. The section 23 contiguous to the end section 20 is provided with a socket to receive the threaded end 22 of said section 20, and the several sections 23 are connected by threaded 25 rods 24, which take into threaded sockets 25 in the contiguous ends thereof, as shown. Any number of the sections 23 may be employed, and the cleaning device may be readily increased in length by adding sections 23 and 30 may be as readily diminished in length by disconnecting some of the said sections.

The resilient or spring strips 9^a of the scraping-plates 9 are connected to the rod-sections 23 by screws 26, and these screws occupy 35 sockets 27, which communicate at their inner ends with the sockets 25. The screws 26 have threads at their inner ends designed to be engaged by the threaded bolts 24, and consequently it will be seen that when the parts 40 are in the position shown in Fig. 8 the screws 26 will be locked against casual turning and a casual disconnection of the resilient strips of the scraping-plates from the rod-sections will be effectually prevented.

45 The end of the threaded rod 5^e is provided with peripheral ribs 30 and is connected to the end section 20 of the rod 7^e by the coupling 31. This coupling 31 comprises two sections 32, which have interior annular grooves 33 to receive the collar flanges or ribs 21 30 of the rods 7^e 5^e, and also have the reduced portions 34 at their ends, as shown. In these reduced portions 34 are formed slots which when the sections 32 are together on the rods 35 5^e 7^e form L or bayonet slots 35. These slots 35 are designed to receive the studs 36 of the rings 37, which serve to hold the coupling-sections 32 together, and when the studs 36 are in the position shown at the right of Fig. 8 it 50 will be seen that the said rings 37 will be secured against casual displacement from the reduced portions of the coupling sections.

The coupling described is strong and durable, and while it may be easily and quickly 55 effected it is not liable to become casually disconnected in practice.

Our improved apparatus is highly efficient

for cleaning the water-tubes of boilers and other apparatus, and it may also be used to advantage for cleaning all other tubes and pipes 70 as well as for scraping other devices.

When desirable, the cleaning device of our improvements may be connected with the piston of an engine other than a steam-engine, and we therefore do not desire to be understood as confining ourselves to the use of a 75 steam-engine.

Having described our invention, what we claim is—

1. In an apparatus for cleaning tubes, the 80 combination of the piston-cylinder of an engine, a piston arranged therein and having a central hollow rod provided with interior threads at its opposite ends and extending through the opposite heads of the cylinder, a 85 threaded rod extending through the hollow piston-rod and engaging the interior threads thereof and having a longitudinal groove, a wheel receiving the threaded rod and having a feather taking into the groove thereof and 90 a cleaning device connected with the threaded rod, substantially as specified.

2. In an apparatus for cleaning tubes, the 95 combination of a main frame, a vertically-adjustable frame arranged on the main frame, the piston-cylinder of an engine carried by the vertically-adjustable frame and having a threaded aperture a rotary screw journaled in the vertically-movable frame and extending 100 through the threaded aperture of the piston-cylinder whereby when the screw is rotated the piston-cylinder will be moved horizontally in the vertically-adjustable frame, a piston arranged in the cylinder and having a threaded aperture and a threaded rod extending 105 through the threaded aperture of the piston, substantially as and for the purpose set forth.

3. In an apparatus for cleaning tubes, the 110 combination of a main frame, a vertically-adjustable frame arranged on the main frame, the piston-cylinder of an engine carried by the vertically-adjustable frame and having a threaded aperture, a rotary screw journaled in the vertically-movable frame and extending 115 through the threaded aperture of the piston-cylinder whereby when the screw is rotated the piston-cylinder will be moved horizontally in the vertically-adjustable frame, a valve-chest carried by and connected with the 120 piston-cylinder, a valve in said chest having a stem extending through the same, a piston arranged in the cylinder and having means for moving the valve-stem and also having a threaded aperture, a threaded rod extending 125 through the threaded aperture of the piston and having a longitudinal groove, an arm connected with the piston-cylinder and a hand-wheel journaled in said arm and having an aperture receiving the threaded rod and a 130 spline entering the groove thereof, substantially as and for the purpose set forth.

4. In an apparatus for cleaning tubes, the combination of the piston-cylinder of an en-

gine, a valve-chest carried by and connected with the piston-cylinder, a valve in said chest having a stem extending through one end thereof, a piston arranged in the cylinder and 5 having the hollow rod extending through opposite heads of the cylinder and provided with interior threads, a threaded rod extending through and engaging the threads of the hollow rod and means on said hollow rod for 10 moving the valve-stem, substantially as and for the purpose set forth.

5. In an apparatus for cleaning tubes, the combination of the main frame comprising brackets adapted to be fastened upon the 15 front of a boiler and having their rear bars pitched or inclined, a vertically - movable frame arranged on said pitched or inclined bars of the brackets, clips adjustably connecting said frame and the inclined bars so 20 as to permit of said frame being raised or lowered and adjustably fixed on the brackets of the main frame, the piston-cylinder of an engine arranged in the vertically - movable frame, means for adjusting the piston-cylinder horizontally in the movable frame, and adjustably fixing the same, and a piston arranged in said cylinder, substantially as and for the purpose set forth.

6. In an apparatus for cleaning tubes, the 30 combination of a main frame, the piston-cylinder of an engine adjustable vertically and horizontally on the main frame, a piston arranged in said cylinder, and a cleaning device adjustably connected with the piston, 35 whereby it may be moved toward or from the same, substantially as specified.

7. In an apparatus for cleaning tubes, the combination of a rod, a plate having teeth or serrations on its outer side, and resilient 40 strips connected at one end to the rod and at their opposite ends to the plate at the opposite ends thereof, substantially as and for the purpose set forth.

8. In an apparatus for cleaning tubes, the 45 combination of a rod, a plate having teeth on its outer side, and the resilient strips connected at one end to the rod and extending laterally and forwardly from the same and connected at their opposite ends to opposite 50 ends of the plate or bar, substantially as specified.

9. In an apparatus for cleaning tubes, the combination of a rod, a circular series of plates surrounding the rod and having teeth on their

outer sides, springs connected at one end to 55 the rod and at their opposite ends to the plates, a second series of plates at the opposite ends thereof surrounding the rod in rear of the first-named series and having teeth on their outer sides, and springs connected at one end 60 to the rod and at their opposite ends to the plates at the opposite ends thereof, the said springs being of a greater length than those of the first-named series of plates, substantially as specified.

10. In an apparatus for cleaning tubes, the combination of a plurality of rod-sections having threaded sockets in their ends, threaded rods arranged between said sections and inserted in the sockets thereof so as to connect 70 the sections, scraping-plates, and resilient strips connected at one end to the rod-sections and at their opposite ends to the plates, substantially as specified.

11. In an apparatus for cleaning tubes, the 75 combination of a plurality of rod-sections having threaded sockets in their ends, and also having laterally-disposed sockets communicating with the end sockets, scraping-plates, 80 strips connected to the scraping-plates, threaded bolts extending through said strips and the laterally-disposed sockets of the rod-sections and having threads at their inner ends, and the threaded rods arranged in the end sockets of the rod-sections to connect said 85 sections and engaging the threaded inner ends of the laterally-disposed bolts, substantially as and for the purpose set forth.

12. In an apparatus for cleaning tubes, the combination of a cleaning device having a 90 rod provided with a collar-flange, a second rod having a collar-flange, and a coupling comprising sections having interior grooves receiving the collar-flanges of the rods and also having reduced portions at their ends 95 having slots forming bayonet-slots, and rings mounted on said reduced portions of the sections and having studs engaging the bayonet-slots of said sections, substantially as and for the purpose set forth.

In testimony whereof we affix our signatures in presence of two witnesses.
